Patented Apr. 18, 1922.

UNITED STATES PATENT OFFICE.

FRANK BERARDI, OF LITTLE SILVER, NEW JERSEY.

DRAIN TILE.

1,413,380.

Specification of Letters Patent. Patented Apr. 18, 1922.

Application filed September 29, 1921. Serial No. 504,046.

To all whom it may concern:

Be it known that I, FRANK BERARDI, a citizen of the United States, residing at Little Silver, in the county of Monmouth and State of New Jersey, have invented certain new and useful Improvements in Drain Tiles; and I do declare the following to be a full, clear, and exact description of the invention, such as will enable others skilled in the art to which it appertains to make and use the same.

This invention relates to an improved drain tile to be used in the formation of conduits which are to be employed for conveying waste materials from a given point to a suitable place of deposit, the tiles being preferably laid under the ground.

One of the principal objects of the invention is to provide an improved tile which is in the form of a casting and includes a substantially semi-cylindrical body which has a portion of its open side closed by a bottom which extends beyond one end of the body and serves, when the conduit is completed, to close the open side of the adjoining tile.

Another object of the invention is to provide a tile embodying the aforesaid construction, the bottom being flat-faced and the extended part serving as a guide which serves to enable the tiles to be quickly connected together and serves to position all of the tiles in correct alinement so as not to hinder the flow of the waste material or liquid.

Another object of the invention is to make the aforesaid bottoms of the tiles sufficiently wide so as to provide anchoring flanges so that when dirt is thrown on top of said flanges, there will be little or no chance of the tiles becoming relatively displaced.

A further object of the invention is to provide tiles of this class which are such in construction that it is not altogether necessary to employ concrete and the like for joining the various tiles together, in view of the fact that the extension of one tile forms a portion of the bottom of the adjoining tile and the dirt thrown on top of the tiles serves to connect the same sufficiently tightly together to overcome leakage.

Other objects and advantages of the invention will be apparent during the course of the following description.

In the accompanying drawings forming

a part of this specification and in which like numerals are employed to designate like parts throughout the same:

Figure 1 is an elevational view of a number of my improved tiles connected together to form a conduit.

Figure 2 is a central longitudinal sectional view on an enlarged scale taken through several of the tiles.

Figures 3 and 4 are sectional views taken substantially on the planes of the lines 3—3 and 4—4 respectively of Fig. 2.

Figure 5 is a side elevational view of one of the tiles.

Figure 6 is a sectional view taken on the plane of the line 6—6 of Fig. 5.

Figure 7 is a top plan view of one of the tiles.

Figure 8 is a longitudinal sectional view taken on the plane of the line 8—8 of Fig. 7.

Before proceeding with a detailed description of the tiles which serve to form the conduit disclosed in Fig. 1, I wish to point out that the intermediate tiles are designated by the numeral 1 while the endmost tiles are

designated by the numerals 2 and 3 respectively. The difference in numbering the various tiles has been selected in view of the fact that the intermediate tiles bearing the numerals 1 are all duplicates while the two endmost tiles are necessarily constructed slightly different. Proceeding with the detailed description, it is to be stated that each of the intermediate tiles comprises an open-ended semi-cylindrical part 4 which has approximately one-half of its open side closed by a substantially rectangular flat-faced bottom 5 which is cast integral with the part 4. It is to be noted that the bottom 5 is sufficiently wide to extend beyond the sides of the part 4, thus providing anchoring flanges 6 which serve a purpose to be hereinafter described.

It is also to be noted that the portion 7 of this bottom 5 extends beyond one end of the part 4 and provides what may be conveniently termed a guide which assists in enabling the various tiles to be quickly engaged with one another and insures proper alinement so that the free flow of liquid or the like through the conduit will not be hindered by any irregularities. It is to be stated here that the extension 7 in addition to providing a guide for accomplishing the above end, this part of the bottom serves to close the open side portion of the adjoining tile when the conduit is completed and

is thereby given an additional function. As above pointed out, all of the intermediate tiles are of the construction just described.

Referring however to the left hand end tile, numbered 2, it will be seen that this tile is not provided with the extended bottom portion and that the semi-cylindrical body portion is slightly longer than the corresponding portions of the intermediate tiles. How-

ever, the extended portion of the adjoining tile serves to close the open bottom or side of this end tile. The remaining end tile, number 3, is provided with the extended bottom and this bottom completely covers the entire open side of the cylindrical body portion as clearly seen in Fig. 1. Inasmuch as other formations of end tiles may be employed, no particular emphasis is laid on the formation of such tiles. On the other hand, the formation of the central or intermediate tiles is of particular value and the specific construction thereof is highly desirable and practical and for this reason, particular emphasis is to be laid on the formation of such tiles. The same reference characters are employed on the corresponding parts of the end tiles as appear on the same parts of the intermediate tiles even though the size of such parts vary slightly.

By carefully considering the drawings it will be seen that in order to form a conduit from my improved tile, the usual ditch is dug and the sections or tiles are so laid that the open ends abut one another in the usual way. However, the extended guide portion 7 of the bottom of one tile forms a portion of the bottom of the adjoining tile as set forth and this extended portion serves to permit the tiles to be guided into engagement and assures proper alinement of the various tiles and at all times holds the adjoining ends of the tiles together and prevents sagging at the point of connection of the tiles. I have found that it is not altogether essential to make use of cement in joining the tiles as the weight of the dirt surrounding the same holds them tightly to-

gether in a substantially leak proof manner. If, however, it is desired to employ cement, this can, of course, be done. Inasmuch as 50 the bottoms of the tiles are sufficiently wide to provide the aforesaid anchoring flanges, it will be seen that when the dirt is thrown on top of these flanges, relative displacement of the tiles will be prevented to a great 55 extent.

Since probably the best results may be obtained with the construction and arrangement herein shown and described, this is taken as the preferred embodiment of the 60 invention. However, I wish it to be understood that minor changes coming within the scope of the subjoined claims may be resorted to if desired.

I claim:

1. A conduit formed of a plurality of detachable sections, each of said sections including a semi-cylindrical part and a bottom which is integral with and closes a portion of the open side of said semi-cylindrical part, 70 said bottom extending beyond one end of said part and serving to close the open side portion of the corresponding part of the adjoining section when the conduit is completed.

2. A drain tile comprising an open end part forming a passage, a portion of the bottom of the latter being open, and a shelf-like extension projecting beyond one end of said part, serving as a means for guiding 80 the tiles into engagement with one another.

3. A tile of the class described comprising a semi-cylindrical body having a portion of its bottom closed by an integral flat-faced substantially rectangular part which is of 85 a width to extend beyond the sides of said body and provide anchoring flanges, said flat-faced part also extending beyond one end of the body and constituting a guide and serving as a part of the bottom of the 90 adjoining tile when in position for use.

In testimony whereof I have hereunto set my hand.

FRANK BERARDI.
